UNITED STATES PATENT OFFICE.

CHARLES C. PECK AND WILLIAM H. CHAPMAN, OF MIDDLEBURY, VERMONT.

ELECTRIC MOTOR.

SPECIFICATION forming part of Letters Patent No. 279,007, dated June 5, 1883.

Application filed January 15, 1883. (No model.)

To all whom it may concern:

Be it known that we, CHARLES C. PECK and WILLIAM H. CHAPMAN, both of Middlebury, in the county of Addison and State of Vermont, have invented certain new and useful Improvements in Electric Motors, of which the following, taken in connection with the accompanying drawings, is a specification.

Our invention relates to that class of electric motors in which the armature rolls upon and in direct contact with the pole-pieces of the magnets alternately from one magnetic field to another; and it consists in an improved form of the pole-pieces of the magnets, whereby the armature is caused to reciprocate in a straight line and the pole-pieces to more closely surround the ends of said armature when at either extreme of its movement.

It further consists in the improved form of pole-pieces, in combination with two or more elastic or spring buffers adapted to aid in checking and reversing the movement of the armature.

It further consists in mounting the ends of the rolling armature in bearings in a yoke or frame adapted to have imparted to it by said armature a rectilinear reciprocating motion, said motion being especially adapted to facilitate connection with certain kinds of mechanism which it may be desired to operate.

It further consists in providing the armature and magnets with disks or collars of brass or other non-magnetic metal at the ends of their respective coils, in order to facilitate the electrical connection of the armature with its coil and to aid in making all of the coils of the same length and contain the same quantity of wire, all of which will be best understood by reference to the description of the drawings and the claims to be hereinafter given.

In the drawings, Figure 1 is a plan of an electric motor embodying our invention. Fig. 2 is a side elevation of the same, and Fig. 3 is an end elevation with a portion cut in section.

A is the bed-plate, made of brass or other suitable non-magnetic metal, and having mounted upon it the two electro-magnets, B and B', composed, respectively, of the coils c and c', cores d and d', and pole-pieces N S and N' and S', said pole-pieces being fastened to the bed-plate A by the screws a a. (Shown

in dotted lines.) The ends of the cores d and d' of the magnets B and B' pass through holes in the pole-pieces N S N' S', and are provided with the nuts b b, by means of which they are securely held in place. Between the pole-pieces of the magnets B and B' are inserted the brass blocks e, shaped and arranged substantially as we have shown and described in another application of even date herewith, except that the upper surface of each of said blocks is made straight instead of curved, and the portions of the contact-surfaces of the pole-pieces N S N' S' which are contiguous to the blocks e are also made straight, so that the armature F will roll back and forth in a straight line, instead of oscillating in a curved path, like a pendulum, as described in our application above cited.

The armature F is of soft iron, cylindrical in form, and is provided with the coil of conducting-wire f. The ends of the armature F are mounted in bearings g g in the frame G, which is provided with the rods g' g', adapted to slide in the bearings H H, secured upon the bed-plate A, and thus guide the frame G in its reciprocating motion, which is imparted to it by the armature F as it rolls upon the contact-surfaces of the pole-pieces N S N' S' and blocks e e, from one magnetic field to the other. The curved surfaces h h of the pole-pieces N S N' S' partially surround the ends of the armature F, and are made of a radius slightly greater than said ends, and the movement of the armature is such that its ends will be brought into close proximity with the surfaces h h, whereby the magnetic force exerted upon said armature will be greatly intensified, and as the reversal of the current takes place when the armature has nearly reached the extreme of its movement in either direction, or is nearest to either of the magnets B or B', said magnet will then exert its maximum repelling force to reverse the motion of the armature. Each of the pole-pieces N S N' S' is provided with an elastic or spring buffer, i, (shown in full in Fig. 2 and in dotted lines in Fig. 1,) which buffers act to prevent the ends of the armature F from coming into actual contact with the surfaces h h, and also aid in checking and reversing the motion of said armature. The buffers i i may be made of rubber of a shape as shown; or they

may be made of any other suitable shape or material, and may be located in any other convenient place. The armature F is provided with two thin disks, k k, of brass or other non-magnetic metal, located at the opposite ends of the coil f, and of a diameter about equal to the diameter of said coil. The ends of the armature F, which rest upon the pole-pieces N S N' S', are made of a diameter slightly greater than the middle portion of said armature, upon which the coil f is wound, thus forming a shoulder just outside of each of the disks or collars k k, said disks being held in place by being confined between said shoulders and the ends of the coil f. In order to place the disks k k upon the armature F, they are each provided with a cut upon one side, as at k', which allows of their being twisted until the ends are sufficiently separated to enable them to be slipped over the middle portion of the armature, when they are bent back to their proper shape, and the armature is then ready to receive its coil. The object of the disks k k is to furnish a convenient means of electrical connection between the armature F and its coil, and to fix the exact length of said coil when being wound upon the armature. After the winding of the coil f is completed it is necessary to place the outer end of the wire in electrical connection with the armature F, which is most readily done by soldering it to the edge of one of the brass disks k. In like manner each of the magnets B and B' is provided with similar disks, l l, held in place between the coils e and e' and the small flanges m m upon the cores d and d', as clearly shown in that portion of Fig. 3 which is cut in section. The portions of the cores d and d' and of the armature F upon which the coils e, e', and f are wound are all of the same diameter, and as the brass disks l l and k k are placed the same distance apart upon said cores and armature, and are of the same diameter, it follows that said disks serve as an accurate guide to enable the same quantity of wire to be placed in each of the three coils, provided the same size of wire is used. Another object of the cuts k' k' in the disks k and l is to prevent electric currents from being induced in said disks, which would be the case were they made in the form of complete rings without such divisions.

A commutator, I, is placed upon the bed-plate A near its center and beneath the armature F. This commutator may be of any suitable construction, and one well adapted for the purpose is shown and described in an application of William H. Chapman, of even date herewith. J and K are two screw-cups set in the pole-pieces N and S, respectively, but insulated therefrom, and serving to connect the battery (not shown) and the various conducting-wires in a circuit in a well-known manner.

A brass spring, n, is secured at one end by the screw o to the frame G, but insulated therefrom, and presses at its other end upon the end of a short wire, p, (the end of which is seen in Fig. 1,) which wire passes through a hole

in the center of the armature F, but insulated therefrom, and connects with the inner end of the armature-coil f.

The wire connections are substantially the same as in our other application before referred to, and are as follows: The outer end of the coil e is connected to the screw-cup J, and the inner end of said coil is connected by wire 75 (not shown) with the inner end of the coil e', while the outer end of the coil e' is connected with one of the springs of the commutator I, the other spring of the commutator being connected by wire r to the screw-cup K. The inner end of the armature-coil f is connected, through the medium of the wire p, spring n, and wire s, to the insulated contact-piece of the commutator I. The outer end of the armature-coil f is in metallic connection with the armature F, as before described, thus connecting it with the frame-work of the machine and to the other two contact-pieces of the commutator, which are also connected to the frame-work of the machine.

The rectilinear reciprocating motion of the frame G is especially adapted where it is desired to transmit such motion directly to the mechanism to be operated, as in working pumps either or both of the rods g' may be 95 the piston rod or rods of pumps or coupled directly to said piston-rods. The mechanism to be driven may be connected with the frame G in any other suitable way—as, for instance, by a connecting-rod attached to either of the rods 100 g', as shown in dotted lines at L, or by two rods, M M, (shown in dotted lines in Fig. 1,) connected to the frame G by the pins t t.

We have illustrated and described an apparatus in which electro-magnets are used and 105 the armature is composed of soft iron and provided with a coil of conducting-wire, it being arranged that the reversal of the current shall take place in said armature-coil; but we do not wish to be limited to this special construction, 110 inasmuch as permanent magnets may be substituted in place of the electro-magnets B and B'; or a permanent magnet in the form of a cylinder may be used in place of the soft-iron armature and its coil with good results by so 115 arranging the wire connections that the current passing through the coils of the magnets B and B' shall be reversed by each movement of the armature.

What we claim as new, and desire to secure 120 by Letters Patent of the United States, is—

1. In an electric apparatus, the combination of an armature provided with curved or cylindrical end portions and adapted to rock or roll from one magnetic field to another, and a pair of U-shaped magnets arranged with their poles in opposition to each other, and having portions of their pole ends shaped and arranged, in connection with the non-magnetic filling-blocks interposed between them, to form 125 straight armature guiding and contact surfaces of lengths not less than the amplitude of the reciprocations of said armature, and the remaining portions curved and arranged to par-

tially surround and inclose two opposite sides of the end portions of said armature and be in close proximity thereto and nearly parallel therewith when said armature is at the extreme of its movement toward said pole-pieces, substantially as and for the purposes described.

2. In an electric apparatus, the combination of an armature provided with curved or cylindrical end portions and adapted to rock or roll from one magnetic field to another, a pair of **U**-shaped magnets arranged with their poles in opposition to each other, and having portions of their pole ends shaped and arranged, in connection with the non-magnetic filling-blocks interposed between them, to form straight armature guiding and contact surfaces, and a yoke or frame connected to the armature and adapted to receive therefrom a rectilinear reciprocating motion, substantially as and for the purposes described.

3. In an electric apparatus, the combination of an armature provided with curved or cylindrical end portions and adapted to rock or roll

from one magnetic field to another, a pair of **U**-shaped magnets arranged with their poles in opposition to each other, and having their pole ends shaped and arranged, in connection with the non-magnetic filling-blocks interposed between them, to form straight armature guiding and contact surfaces, and a yoke or frame connected to the armature and adapted to receive therefrom a rectilinear reciprocating motion, substantially as and for the purposes described.

4. In an electric apparatus composed of two electro-magnets arranged with their poles in opposition, and an armature provided with a coil of conducting-wire and adapted to rock or roll from one magnetic field to another, disks or rings of non-magnetic metal secured upon the cores of the magnets or armature at the ends of their respective coils, and cut open upon one side, substantially as and for the purposes described.

In testimony whereof we have signed our names to this specification, in the presence of two subscribing witnesses, on this 13th day of January, A. D. 1883.

CHARLES C. PECK.
